W. C. McClain, Jr.
Attorney

UNITED STATES PATENT OFFICE.

WADE C. McCLAIN, OF LITTLE ROCK, ARKANSAS.

DENTIPHONE FOR PHONOGRAPHIC USE.

Application filed May 27, 1924. Serial No. 716,238.

This invention relates to a dentiphone or audiphone for use by the deaf in order that the sounds from a phonograph or the like may reach the auditory nerve through the 5 teeth and bones of the head.

It is aimed to provide a novel, simplified and efficient construction to attain the purpose stated and particularly one which has a stylus securing means of the form or its 10 equivalent, as hereinafter disclosed.

An operative embodiment is shown in accompanying drawings, wherein:—

Figure 1 is a view in perspective showing the invention as used in connection with a 15 phonograph;

Figure 2 is a view in perspective, showing the parts at the stylus end, disassociated;

Figure 3 is a cross sectional view taken on the line 3—3 of Figure 1 and through the 20 stylus securing means;

Figure 4 is a vertical sectional view passing through the stylus securing means; and

Figure 5 is a perspective view of the mouth 25 end of the device.

Like reference characters designate like or similar parts in the different views.

In carrying out the invention, a sound-transmitting element 10 is provided of suitable length, preferably being made from 30 highly tempered spring steel. This element at one end carries a stylus 11 adapted to coat with the sound groove of a record conventionally shown at 12 and over which an arm 15 is movable to permit the usual movement of the stylus 11, that is to say, the arm 35 is swiveled so as to move both vertically and laterally.

The end of the element 10 which carries the stylus 11 has spaced lugs 16 and a lug 17 spaced from the same and located intermediate them. The stylus 11 is removably secured in a socket 12 of the holder 18 as by 40 a set screw 19, in such manner that the stylus will directly contact with the element 10.

The upper end of the holder 18 is bifurcated to provide a slot 20 which receives the lug or projection 17. A movable bridge bar 21 transversely crosses the holder 18 and then passes intermediate the lugs 16 and 17 45 and has its terminals engaged against said lugs 16 at the opposite side of the element 10 through its intermediate portion which engages the holder as aforesaid. Securing screws 22 pass through holes 23 in the outer 50 terminals of the bridge bar 21 and then through notches 24 in the outer edges of the

lug 16. Said screws 22 not only serve to clamp the bridge bar in order to in turn clamp the holder to the element 10, but they clamp the bridge bar and element 10 together and also fasten them to the arm 15, preferably to an extension 26 of a head 27, which may be removably carried by arm 15 being fastened thereto by screws or the equivalent 28.

The mouth end of the element 10 may be thickened as at 29 and the thickened portion thus provided is adapted to be held in the mouth of the user and firmly engaged by the teeth. To prevent accidental disengagement of the teeth, the portion 29 at its distal end is preferably provided with a continuous lateral flange 30.

The element 10 obviously may have branches each equipped with the portion 29 and a flange 30 to enable simultaneous use of the device by a number of persons.

In use, with the stylus 11 arranged to travel in the usual manner in respect to the sound grooves of records such as 12, the portion 29 is held in the mouth, firmly engaged by the teeth of the user. As the stylus 11 is in contact with the element 10, the vibration imparted to the stylus by the sound groove will in turn be transmitted to the element 10 and from the latter through the teeth and bones of the head to the auditory nerve. As a result, the device is particularly adapted for use by deaf persons so that they may hear and enjoy the playing of phonograph 80 selections.

It is to be understood that I have used the term "phonograph" in its broadest sense and as thus including analogous devices or specific phonograph adaptations such as 85 commercial talking machine records.

Various changes may be resorted to provided they fall within the spirit and scope of the invention.

What is claimed is:—

1. In combination the swiveled arm of a talking machine, and a head on said arm, a sound transmitting element adapted for contact with the teeth of the user, a bridge bar secured to said head and engaged by 105 said element, and a stylus carried by said element and adapted for coaction with a sound record.

2. In combination with the swiveled arm of a talking machine, and a head on said 110 arm, a sound transmitting element of resilient material adapted for contact with the

teeth of the user, a bridge bar secured to said head and engaged by said element, and a stylus carried by said element and adapted for coaction with a sound record.

- 5 3. A device of the class described having a sound transmitting element adapted for engagement with the teeth, a stylus holder bifurcated to straddle a portion of the element, a bridge bar disposed across said holder, and means to secure said bridge bar and holder to a support, the last mentioned means serving to clamp the holder to the element.
- 10 4. A device of the class described having a

sound transmitting element adapted for engagement with the teeth, said element having three lugs at one end, a bifurcated stylus holder straddling the intermediate lug, a bridge bar disposed across said holder and passing intermediate the lugs so as to engage the outer lug at the reverse side of the element to that of its bridge portion, and fastening means passing through the bridge bar adjacent its terminals engaging said element and adapted for connection to a support.

In testimony whereof I affix my signature.

WADE C. McCRAIN,
